CIGARETTE LIGHTER

Rueben C. Springborn, Iola, Wis.

Application March 26, 1940, Serial No. 326,095

1 Claim. (Cl. 219—32)

The present invention relates to new and useful improvements in cigarette lighters particularly for automobiles and has for one of its important objects to provide, in a manner as hereinafter set forth, a device of this character embodying means for forcing air through the cigarette while it is being lighted.

Another very important object of the invention is to provide, in a cigarette lighter of the type including an electric igniter and draft means, a novel construction and arrangement for controlling said ignited and draft means upon insertion and withdrawal of a cigarette.

Other objects of the invention are to provide a cigarette lighter of the character described which will be comparatively simple in construction, strong, durable, highly efficient and reliable in use, compact and which may be manufactured at low cost.

All of the foregoing and still further objects and advantages of the invention will become apparent from a study of the following specification, taken in connection with the accompanying drawing wherein like characters of reference designate corresponding parts throughout the several views, and wherein:

Figure 1 is a view in side elevation of a cigarette lighter constructed in accordance with the present invention.

Figure 2 is a view in vertical longitudinal section through the device.

Figure 3 is a cross sectional view, taken substantially on the line 3—3 of Figure 2.

Referring now to the drawing in detail, it will be seen that the embodiment of the invention which has been illustrated comprises a tube 1 of suitable material. At one end, the tube 1 terminates in a reduced, threaded neck 2 which extends through an opening provided therefor in the instrument panels of an automobile. Threaded on the neck 2 is a substantially bell shaped guide 4 which is adapted to secure the tube 1 on the instrument panel 3. The guide 4 also facilitates proper insertion of the cigarette to be lighted, as at 5. Connected to the other end portion of the tube 1 is a flexible conduit or hose 6. The hose 6 is to extend to a point adjacent the rear of the cooling fan of the engine of the automobile for receiving air under pressure therefrom. The end of the hose which is adjacent the fan may be provided with a substantially funnel shaped or conical guide for directing air into said hose from the fan.

Mounted on the forward portion of the tube 1 and depending therefrom is a casing 7 of suit-

able material. The casing 7 is removably secured to the tube 1 by screws 8. As seen in Fig. 2 of the drawing, the tube 1 is provided in its lower portion with an opening 9 for communication with the casing 7.

Mounted in the casing 7 and extending upwardly into the tube 1 is a rigid post or bracket 10. Mounted on the upper end portion of the post 10 and electrically insulated therefrom is a stationary contact 11. A conductor wire 12 enters the casing 7 through an opening 13 provided therefor and is connected to the contact 11. The conductor 12 connects the contact 11 with a suitable source of current supply, such as the usual storage battery of the vehicle.

Also mounted in the casing 7, forwardly of the post 10, is an upstanding resilient arm 14. Mounted on the upper end portion of the resilient arm 14 for movement in the forward portion of the tube 1 is an igniting head which is designated generally by the reference numeral 15. The igniting head 15 includes a substantially cup-shaped cap 16 having formed therein a centrally located aperture 17 which, as best seen in Fig. 2 of the drawing, is adapted to be closed by the cigarette 5. Mounted in the cap 16 is a coiled electric heating element 18. The element 18 is provided with a center contact 19 which is engageable with the contact 11. Of course, the periphery of the element 18 is grounded for completing the electric circuit when the contact 19 is engaged with the contact 11.

The reference numeral 20 designates a butterfly valve which is mounted in the tube 1 for controlling the flow of air therethrough. The air control valve 20 is operatively connected to the igniting head 15 for actuation thereby through the medium of a link 21.

It is thought that the operation of the lighter will be readily apparent from a consideration of the foregoing. The igniting head 15 and the valve 20 are normally in the position shown in Fig. 2 of the drawing, in which position the contacts 11 and 19 are spaced from each other and the tube 1 is closed against the passage of air therethrough. The cigarette 5 to be lighted is inserted and engaged with the cap 16 over the opening 17, the guide 4 facilitating this. The cigarette 5 is then pushed inwardly in a manner to flex the resilient arm 14 and engage the contact 19 with the contact 11 thus completing the electric circuit through the element 18 and bringing said element to incandescence. This movement of the igniting head 15 opens the valve 20 through the medium of the link 21 thereby

permitting the flow of air through the tube 1. This air flows with sufficient force to pass through the element 18, the opening 17 and the cigarette 5 thereby accelerating the ignition of said cigarette and putting a live light thereon. When smoke is observed coming from the outer end of the cigarette the operator will know that said cigarette has been properly lighted. As soon as the cigarette is withdrawn the resilient arm 14 returns the igniting head 15 to the position seen in Fig. 2 of the drawing thereby disengaging the contact 19 from the contact 11 for opening or breaking the electric circuit to the element 18 and at the same time returning the valve 20 to closed position. Referring again to Fig. 2 of the drawing, it will be observed that the apertured cap 16 prevents the cigarette 5 from contacting the element 18. The removable casing 7 permits access to be readily had to the igniting head 15 should the element 18 burn out.

It is believed that the many advantages of a cigarette lighter constructed in accordance with the present invention will be readily understood and although a preferred embodiment of the

device is as illustrated and described, it is to be understood that changes in the details of construction and in the combination and arrangement of parts may be resorted to which will fall within the scope of the invention as claimed.

What is claimed is:

A cigarette lighter comprising a tube for connection at one end with a source of air under pressure, the other end portion of said tube for the reception of a cigarette to be lighted, an air control valve mounted in the tube, a casing mounted on the tube and communicating therewith, a post in the casing extending into the tube, a stationary, insulated contact on said post, a resilient arm in the casing extending into the tube, an igniting head on said resilient arm including an electric element and a contact engageable with the first named contact, said igniting head being movable by the cigarette for engaging the contacts, and a link operatively connecting the valve to the igniting head for actuation thereby.
